UNITED STATES PATENT OFFICE.

MARY ELIZABETH BISHOP, OF BROOKLYN, NEW YORK, ASSIGNOR TO DECORATIVE ARTS LEAGUE, OF JERSEY CITY, NEW JERSEY, A CORPORATION OF NEW JERSEY.

DESIGN FOR A LAMP.

Application filed June 13, 1923. Serial No. 6,487. Term of patent 14 years.

To all whom it may concern:

Be it known that I, MARY E. BISHOP, a citizen of the United States, residing at Brooklyn, in the county of Kings and State of New York, have invented a new and original design for Lamp, of which the following is a specification, reference being had to the accompanying drawing, forming part thereof.

The figure is a side view of the lamp showing my new design.

I claim:

The ornamental design for a lamp, as shown.

In testimony whereof, I have hereunto signed my name.

MARY ELIZABETH BISHOP.
